UNITED STATES PATENT OFFICE

105,861

DESIGN FOR A DOLL

Mollye Goldman, Darby, Pa.

Application June 11, 1937, Serial No. 69,781

Term of patent 14 years

To all whom it may concern:

Be it known that I, Mollye Goldman, a citizen of the United States, residing at Darby, in the county of Delaware and State of Pennsylvania, have invented a new, original, and ornamental Design for a Doll, of which the following is a specification, reference being had to the accompanying drawing, forming part thereof.

In the drawing:

Fig. 1 is a front elevational view of a doll embodying my invention.

Fig. 2 is a rear elevational view of the doll embodying my invention.

I claim:

The ornamental design for a doll substantially as shown.

MOLLYE GOLDMAN.
